SHOE

Abe Sedley, Beachwood, Ohio, assignor to International Seaway Trading Corporation, Cleveland, Ohio

Filed Oct. 29, 1971, Ser. No. 194,083

Term of patent 14 years

Int. Cl. D2—04

U.S. Cl. D2—310

Fig. 1

Fig. 2

FIG. 1 is a side elevational view of a shoe showing my new design;

FIG. 2 is an opposite side elevational view of the shoe shown in FIG. 1.

The characteristic feature of my design resides in the combination on a shoe having a sole portion and an upper as shown of a toe covering and a similar heel covering over the sole and part of the upper all as shown on the drawing.

I claim:

The ornamental design for a shoe, substantially as shown and described.
